UNITED STATES PATENT OFFICE

2,560,559

GASOLINE OPERATED PNEUMATIC TOOL

Henry C. Dearborn, United States Navy

Application December 10, 1945, Serial No. 634,126

3 Claims. (Cl. 123—7)

(Granted under the act of March 3, 1883, as amended April 30, 1928; 370 O. G. 757)

1

This invention pertains to improvements in a gasoline operated pneumatic tool and especially to a device designed as a hammer, vibrator, or pavement breaker.

Ordinarily pneumatic tools are operated by compressed air supplied by a compressor operated by a high horsepower engine.

An object of this invention is to provide a small, low-horsepower combustion engine capable of supplying the necessary combustion fuel mixture to a combustion chamber in the pneumatic tool.

Another object of this invention is to provide a pneumatic tool which is compact, light in weight, and is easily portable.

Details of the invention are described in connection with the following drawings in which:

Fig. 1 is a diagrammatic showing of the assembly;

Fig. 2 is a longitudinal cross section of the engine;

Fig. 3 is a section of the cylinder head in the pneumatic tool;

Fig. 3a is an intermediate section of the pneumatic tool; and

Fig. 3b is the lower section of the pneumatic tool.

The device as shown consists of a small two stroke cycle gasoline engine 60 which supplies compressed combustible fuel to a combustion chamber in the pneumatic tool 50. Although the engine is shown as a separate unit, it would be practical to mount the small engine directly on the pneumatic tool to become an integral part thereof.

Details of the engine design are shown in Fig. 2. Crankshaft 101 has two throws one of which is connected by means of connecting rod 120 to piston 109 in cylinder 108. Cylinder 108 is the power cylinder. The other throw of crankshaft 101 is connected by means of connecting rod 121 to piston 111 in cylinder 110. Cylinder 110 is the compression cylinder and compresses the combustion fuel for the combustion chamber of the pneumatic tool.

It will be observed that pistons 109 and 111 travel towards each other simultaneously and in so doing cause crankcase compression in the crankcase. The gas so compressed has been drawn into the crankcase through the carburetor 40 and through poppet valve 116. When the pistons reach the bottom of the stroke, piston 109 uncovers exhaust port 105, and then uncovers intake port 122. This is conventional two stroke engine design. Piston 111 uncovers intake port

2

123 only. On the return stroke a low pressure condition is set up in the crankcase which then draws in a new charge of combustible fuel. Piston 109 advances towards spark plug 42 and into firing position while piston 111 forces its compressed charge through valve 112 into manifold 115 which is connected to the pneumatic tool by means of flexible tube 36. To avoid building up excessive pressures in the line, a spring loaded by-pass valve 113 is provided which permits passage through manifold 114 into the crankcase, thereby permitting excess compressed fuel to be returned to the crankcase.

Crankshaft 101 carries flywheel 102 which is provided with groove 103 adapted to receive a rope starter. Flywheel 102 is provided with fan blades 104 and 105 on its circumference. These blades provide a cooling flow of air over the cylinders. Mounted on the underside of the flywheel are permanent magnets 106 and 106' which are carried past field coils 107 to provide low tension current for a purpose later described.

Compressed fuel in engine manifold 115 is conducted through hose 36 to a manifold 41 on the pneumatic tool. Passage of this gas is controlled by poppet valve 30 which can be opened or closed by the operator upon moving grip lever 12, inasmuch as lever 12 is connected by link 31 and lever 32 to operate valve 30. Upon opening of valve 30, gas under pressure passes into the cylinder head manifold of the pneumatic tool and, being under pressure, opens valve 14. Valve 14 is normally held in closed position by lever 22 which is lifted by spring 20. Relatively low pressure in this manifold will cause valve 14 to open.

Compressed fuel is thus conducted to combustion chamber 34. Piston 1 below combustion chamber 34 is held against compression by means of long coil spring 7.

Passageway 29 in the tool cylinder head conducts the gas to a diaphragm switch 15. When a predetermined pressure is reached diaphragm 15 is distorted to provide an electrical connection across posts 16 and 17. Electrical energy supplied by the engine magneto is fed through a three cable conduit 9 through line D to energize magnets 21. This results in a lifting action on lever 22 to cause valve 14 to seat. The same connection causes a flow of current through wire 50 A to energize a relay which makes a circuit with a high tension coil thereby producing a spark producing current which is conducted by high tension line 19 to spark plug 23. The spark thus produced ignites the charge in combustion chamber 34 causing piston 1 to strike anvil 26.

The force of the blow on the anvil is transmitted to tool bit 25. This bit is removable and interchangeable to permit the use of various types of tools and is retained by retainer spring 24.

Piston 1 at the bottom of its stroke uncovers ports 27A and 27B in cylinder 2. These ports permit the escape of burned fuel. Pressure being thus relieved in the combustion chamber results in automatic opening of valve 14 to permit an inflow of fresh gas which is compressed by the returning piston propelled by spring 7.

As previously stated, escaping gas after combustion is ejected through ports 27A and 27B and in flowing through these ports is conducted through openings in the handle support assemblies 28 and 29. The flow of exhaust gas through ports 27A and 27B will set up a flow of air, which will cool the fins on cylinder 2.

Since it is standard practice to mix lubricating oil with the fuel in a two stroke cycle engine, adequate lubrication will be provided by the fuel.

The engine is built as small as practical for the obvious purpose of obtaining maximum weight reduction. The speed of the engine must be adequate to provide the desired flow of combustible mixture. Thus, if the engine has only one third the displacement of the hammer it would be necessary to run the engine at 3000 R. P. M.'s to provide 1000 hammer blows per minute.

It will be apparent that the assembly may be modified by substituting a four stroke cycle engine to pump the combustible fuel or there may be a unit to pump only air with means provided to inject fuel. The body of the pneumatic tool may be of any desired conventional design.

The invention described herein may be manufactured and used by or for the Government of the United States of America for governmental purposes without the payment of any royalties thereon or therefor.

Having described my invention, I claim:

1. In a pneumatic tool providing a tool bit, the combination of a head for said tool bit, a combustion chamber, a piston engageable with said head reciprocable in said chamber, an exhaust port uncovered by said piston at one end of its stroke, a spring for returning said piston to operative position, a manifold connected to said chamber by a port, a solenoid operated valve located in said port, ignition means in said chamber, a switch responsive to pressure in said chamber for simultaneous operation of said solenoid and said ignition means by an electrical current, a second port opening into said manifold, and a separate compressor for fuel connected to said second port by flexible conduit, said compressor comprising one cylinder of a two cylinder two cycle internal combustion engine having one carburetor for supplying fuel to the cylinder used as a compressor and to the other or driving cylinder and having a by-pass conduit connecting said flexible conduit with said crankcase with a pressure responsive valve in said by-pass, where-

by said compressor supplies the tool with a fuel-air mixture at a constant pressure.

2. A tool comprising a combustion chamber, a piston slidable in said combustion chamber adapted to impart striking force to a tool bit, valve means opening into said combustion chamber for admitting a fuel charge, an exhaust port opening into said combustion chamber, a constant pressure compressor consisting of two cylinders mounted on and opening into a crankcase, a piston in each cylinder operative together on one crankshaft in said crankcase, a carburetor adapted to admit a fuel charge to said crankcase, passages connecting said crankcase with a port in the lower end of each of said cylinders for the conduction of fuel charges thereto, said ports being uncoverable by said pistons at their down-stroke position, a conduit connecting the first of said cylinders with said valve means on said combustion chamber, a pressure relief valve connecting said conduit with said crankcase, a second exhaust port on the second of said cylinders, and ignition means for the second of said cylinders and said combustion chamber.

3. A constant pressure compressor for supplying a fuel-air mixture to a portable explosively operated tool at a constant pressure comprising two cylinders mounted on and opening into a crankcase, a piston in each cylinder operative together on one crankshaft in said crankcase, a carburetor adapted to admit a fuel charge to said crankcase, passages connecting said crankcase with a port in the lower end of each of said cylinders for the conduction of fuel charges thereto, said ports being uncoverable by said pistons at their down-stroke position, a flexible conduit connecting the first of said cylinders with the inlet of the tool, a by-pass connecting said crankcase with said conduit, a pressure responsive valve in said by-pass, an exhaust port on the second of said cylinders, and ignition means for the second of said cylinders.

HENRY C. DEARBORN.
